UNITED STATES PATENT OFFICE.

CHARLES F. LEFEVER, OF PLYMOUTH, MICHIGAN, ASSIGNOR TO DAISY MANUFACTURING COMPANY, OF PLYMOUTH, MICHIGAN, A CORPORATION OF MICHIGAN.

LIQUID-GUN.

1,180,856.

Specification of Letters Patent. Patented Apr. 25, 1916.

Application filed December 16, 1915. Serial No. 67,192.

To all whom it may concern:

Be it known that I, CHARLES F. LEFEVER, a citizen of the United States of America, residing at Plymouth, in the county of 5 Wayne and State of Michigan, have invented certain new and useful Improvements in Liquid-Guns, of which the following is a specification, reference being had therein to the accompanying drawings.

10 The invention relates to liquid guns of that type in which the liquid is ejected by the telescopic collapsing of the barrel, and it is the primary object of the present invention to provide means for firing a succession of shots without the necessity for recharging.

15 It is a further object to accomplish this result without complication in the construction, and further to obtain various features 20 of advantage as hereinafter set forth.

In the drawings I have shown my invention as applied to a water pistol; in which—

25 Figure 1 is a central longitudinal section therethrough; Figs. 2 and 3 are perspective views of the parts of the telescopic barrel detached; and Fig. 4 is a view similar to Fig. 1 showing the gun fully charged.

30 A is the frame or casing of the pistol, which is formed of a sheet metal stamping having complementary embossed sections abutting against each other and forming both the false barrel and the handle.

35 B is a telescopic extension of the barrel provided with a trigger and guard portion C, preferably formed integral therewith as a single sheet metal stamping.

40 D is a true barrel or magazine for containing the liquid, which telescopically engages the extension barrel B and is movable therewith and with the trigger section C..

E is a piston within the barrel D, which is connected by a tube F to the apertured end of the barrel B, and is movable therewith.

45 G is a ratchet rod extending within the frame A parallel to the barrel D, and H is a pawl or detent on the barrel D which is operatively engaged with said ratchet member. The ratchet bar G is double-acting, being provided with teeth upon opposite sides thereof which are oppositely inclined so that by reversing the bar its engagement with the pawl or detent H is reversed. Thus in the position shown in Fig. 1 the pawl H will 55 engage the teeth G' of the bar G and will be

held thereby from outward movement with the telescopic barrel B, while permitting inward movement therewith. On the other hand, in the reverse position, shown in Fig. 4, the ratchet teeth G' will engage the pawl H, holding the barrel D from inward movement with the barrel B, while permitting outward movement therewith.

The construction just described is one which permits of employing a barrel D of greater length than the telescopic movement permitted the barrel B, so that when said barrel D is completely filled it will hold a liquid charge sufficient for a number of shots. To fill the barrel the ratchet bar G is turned 70 into the position shown in Fig. 1. The discharge end of the pistol is then immersed in water, and by then reciprocating the trigger section C a plurality of times said barrel D will be moved inward with a step-by-step movement until completely filled. This movement is due to the fact that the barrel D frictionally engages the barrel B, and will therefore move therewith when permitted, which is the case during the inward movement, as shown in Fig. 1. On the other hand, during the outward movement the dog H engaging the ratchet teeth G' will hold the barrel D from movement, so that the friction of the outer barrel B will be overcome and the latter will move independently.

When the pistol is charged with liquid in the manner above described it is capable of firing a number of shots, the ratchet bar G being first reversed in position so as to engage the ratchet teeth G' with the detent H. When thus arranged the barrel D is locked from inward movement, and consequently the inward movement of the trigger section C and barrel B will force the piston E in 90 the barrel D to displace a portion of the liquid therefrom, which is discharged through the tube F. Upon the upward movement of the telescopic barrel B, the barrel D will be carried thereby without 100 relative movement to the piston, but upon the succeeding inward movement of the trigger section it will again be held stationary and additional liquid discharged therefrom. This action may be continued until the entire liquid contents of the barrel is discharged.

To simplify the manufacture of the pistol the ratchet bar G is formed of a stamping having a head portion G' with a narrow 110

neck portion G⁴ which engages an aperture formed in the meeting edges of the frame or casing A. This forms an anchoring connection between the bar G and the frame, 5 and at the same time it permits of rotating the bar to reverse the engagement of the ratchets. A second bar I having a similar head J is engaged with an aperture in the meeting edges of the frame and forms a 10 guide for a spring K bearing against the trigger member C, to force the telescopic barrel B outward.

While I have described a specific construction of means for successively discharging portions of the contents of the magazine barrel, it is obvious that other devices may be employed for the same purpose. In all 15 of these various modifications, however, the length of the magazine barrel must be greater than the length of the telescopic movement, so that more liquid can be stored 20 than is discharged at one time.

What I claim as my invention is:

1. A liquid gun, comprising a telescopic barrel, trigger-actuating means for collapsing said barrel, a magazine barrel of greater length than the collapsing movement of said telescopic barrel, and means actuated by the collapsing movement of said 25 barrel for successively discharging portions of the contents of said magazine barrel.

2. In a liquid gun, the combination with a magazine barrel, of a piston therefor, a reciprocating trigger mechanism, and means 30 actuated thereby for relatively moving said piston and barrel step-by-step to successively discharge portions of the liquid contents.

3. In a liquid gun, the combination with a magazine barrel and a coöperating piston, 35 of trigger-actuating means for relatively moving said piston and barrel step-by-step to successively discharge portions of the liquid contents.

4. In a liquid gun, the combination with a magazine barrel, of a telescopically collapsible barrel inclosing the same, one of the telescopic sections being in frictional engagement with said barrel, a piston engaging 40 said magazine barrel anchored to the opposite member of said telescopic barrel, and means for holding said magazine barrel from movement by the friction of said telescopic barrel when actuated in one direction, 55 while permitting movement therewith in the opposite direction.

5. In a liquid gun, the combination with a telescopically collapsible false barrel, of a magazine barrel inclosed therein and frictionally engaged with one of the telescopic sections, said magazine barrel being of greater length than the telescopic movement, and means for holding said magazine barrel from frictional actuation in the 60 movement of said telescopic barrel in one

direction, while permitting such frictional movement in the opposite direction, whereby a step-by-step advance is produced.

6. In a liquid gun, the combination with a telescopically collapsible false barrel, of a 70 magazine barrel inclosed thereby, being of greater length than the telescopic movement and frictionally engaged with one of the telescopic sections, a piston engaging said magazine barrel secured in fixed relation to said frictionally-engaging telescopic section, and means for holding said magazine barrel against frictional actuation during the collapsing telescopic movement while permitting frictional movement during the 80 expanding telescopic movement.

7. In a liquid gun, the combination with a telescopically collapsible false barrel, of a magazine barrel inclosed in said telescopic barrel, being greater in length than the 85 telescopic movement and frictionally engaging one of the telescopic sections, a piston engaging said magazine barrel anchored to said frictionally-engaging telescopic section, and means engaging said magazine barrel for holding the same from frictional actuation by said telescopic section alternatively in opposite directions.

8. In a liquid gun, the combination with a collapsible false barrel, of a magazine barrel inclosed thereby, being of greater length than the telescopic movement and frictionally engaging one of the telescopic sections, a piston engaging said magazine and anchored to said frictionally-engaging telescopic section, and a ratchet and pawl connection for holding said magazine barrel from frictional actuation in one direction and permitting such actuation in the opposite direction to produce a step-by-step relative movement of said barrel and piston.

9. In a liquid gun, the combination with a telescopically collapsible false barrel, of a magazine barrel therein of greater length than the telescopic movement and frictionally engaging one of the telescopic members, a piston in said magazine anchored to said frictionally-engaged telescopic member, a ratchet bar anchored to the opposite of said telescopic members, and a pawl on 110 said magazine barrel engaging said ratchet bar to produce a step-by-step relative movement of said piston and magazine in successive collapsing movements of said telescopic sections.

10. In a liquid gun, the combination with a telescopically collapsible false barrel, of a magazine barrel inclosed thereby of greater length than the telescopic movement and frictionally engaging one of the telescopic sections, a reversible ratchet bar anchored to the opposite one of said telescopic sections, and a pawl on said magazine barrel engaging said ratchet bar to be held thereby from frictional actuation in one direc- 125 130

tion, said direction of movement being reversed upon the reversal of said ratchet bar.

11. In a liquid gun, the combination with a sheet metal case formed of complementary sections having abutting edges, of a member extending in said case having a notched end engaging the abutting flanges of said complementary sections to be anchored thereby.

12. In a liquid gun, the combination with a false barrel, of a magazine barrel therein, a piston coöperating with said magazine barrel, a reciprocating trigger mechanism, and means actuated by successive movements of said trigger mechanism for relatively moving said magazine barrel and piston step-by-step.

13. In a liquid gun, the combination with a false barrel, of a magazine barrel longitudi-

nally movable within said false barrel and having liquid capacity for a plurality of shots, a piston in said magazine barrel, a reciprocatory trigger mechanism connected with said piston, and means coöperating with said magazine barrel permitting the step-by-step movement thereof with said piston upon the actuation of the same in one direction by said trigger mechanism and holding said barrel stationary during the movement of said piston in the opposite direction.

In testimony whereof I affix my signature in presence of two witnesses.
